J. KAHN

METALLIC JOIST

Filed May 23, 1925

INVENTOR.

Julius Kahn
Francis D. Hardesty
his ATTORNEY.

UNITED STATES PATENT OFFICE.

JULIUS KAHN, OF YOUNGSTOWN, OHIO, ASSIGNOR TO TRUSCON STEEL COMPANY, OF YOUNGSTOWN, OHIO, A CORPORATION OF MICHIGAN.

METALLIC JOIST.

Application filed May 23, 1925. Serial No. 32,496.

The present invention relates to structural elements for buildings and more specifically for metallic joists.

Among the objects of the invention is a light strong rigid joist which shall have the maximum strength and rigidity for its weight and dimensions.

Another object is the production of such joists in an efficient and economical manner so as to reduce waste as scrap or as unstressed metal.

With these and other objects in view as will readily appear to those skilled in the art, the invention consists broadly in a joist fabricated of sheet metal in the manner and form indicated in the following description and drawings, in which:

Fig. 1 is a plan view of strip of metal showing how such strip is first treated.

Fig. 2 is an elevation of a portion of a finished joist.

Fig. 3 is a section on line 3—3 of Fig. 1.

Fig. 4 is a section on line 4—4 of Fig. 1.

Fig. 5 is a section on line 5—5 of Fig. 2.

Fig. 6 is a section on line 6—6 of Fig. 2.

As indicated in the drawing the joist forming the subject matter of the invention is produced by starting with a flat strip of metal 10 and cutting along the line 11 to produce two mated strips 12 and 13 each consisting of a chord portion 14 with laterally projecting triangular portions 15 spaced from each other and having the apexes of the triangles integral with the chord portion. Previous to the cutting operation or simultaneous therewith or even after the cutting operation the triangular portion 15 may be ribbed along the two sides as at 16 and a small triangular piece of metal may also be removed as at 17. The removal of the small triangle lessens the weight of metal in the finished element but does not materially reduce the strength.

The cut out strips so formed are then placed end to end with one reversed and the chord portions butt-welded after which an element of I-beam section is produced by spot-welding on either side of the chord portion as at 18 an angle iron 20 to form one base and on either side of the bases of

the triangles as at 19 to form the other base.

In order to produce a more rigid supporting end on the element so formed there may be welded at the end of the element two small channels 21 as is indicated in Figs. 2 and 6 and these channels allowed to project beyond the lower base portion produced by welding the angle irons onto the chord portion of the web. The channels 21 will be spot-welded to the ends of the angle irons as at 21a.

By following the above procedure there is produced a light strong building element which has the maximum strength for the weight of metal used and which may be produced economically because of the small waste of metal.

Having now described the invention and the preferred embodiment thereof, it should be understood that it is not to be limited to the precise details given but is to be limited only by the scope of the claims which follow.

I claim—

1. A metallic joist consisting of a sheet metal web portion cut out to form a chord portion with spaced triangular portions projecting laterally therefrom with their apexes integral with said chord portion, and having flat upper and lower surfaces formed by welding angle irons to the sides of said chord portion and to the sides of the bases of the triangles.

2. A metallic joist consisting of a sheet metal web portion cut out to form a chord portion with spaced triangular portions projecting laterally therefrom with their apexes integral with said chord portion, and having flat upper and lower surfaces formed by welding angle irons to the sides of said chord portion and to the sides of the bases of the triangles and also having extended supporting chord portions formed of narrow channel members welded back to back and to the bases of the end triangles and made continuous with the upper angle irons by butt-welding.

3. A metallic joist consisting of an I-beam having a web of sheet metal cut out to form a narrow continuous chord portion

with spaced triangular web portions having their apexes integral with the chord portion, the web having base members welded to the chord portion and to the bases of the triangular angles.

4. A metallic joist consisting of an I-beam having a web of sheet metal cut out to form

a narrow continuous chord portion with spaced laterally extending bars, the web having base members welded to the chord portion and to the outer extremities of said bars.

JULIUS KAHN.
